UNITED STATES PATENT OFFICE.

FENELON McCOLLUM, JR., OF MANSFIELD DEPOT, CONNECTICUT.

FIGURE WHEELED TOY.

Application filed November 8, 1923. Serial No. 673,587.

To all whom it may concern:

Be it known that I, FENELON McCOLLUM, Jr., a citizen of the United States, and a resident of Mansfield Depot, county of Tolland, State of Connecticut, have invented certain new and useful Improvements in Figure Wheeled Toys, of which the following is a specification.

The object of the present invention is to provide an improved toy wherein a figure, such as a horse, has imparted to it a rocking or galloping motion as the toy is rolled or wheeled over a surface. The particular aim of the invention is to provide a toy of this sort having features of novelty and advantage and which is specially characterized by its extreme simplicity in construction and the very low cost at which it may be manufactured and sold.

20 In the accompanying drawing:

Figure 1 is a side elevational view of the toy with a portion of the handle being broken away;

25 Fig. 2 is a top plan view on a smaller scale, the figure or horse being removed; and

Fig. 3 is a sectional view on a vertical plane including the axis of the wheel or roller.

30 In the drawing, *a* denotes a disk or wheel adapted to be rolled upon the ground or floor; *b* is a handle portion in the forward end of which is journalled the wheel *a*; and *c* is a figure, which is in the form of a horse, pivoted to the handle. The figure is provided at its lower forward portion with a pair of inwardly projecting pegs *e* which engage in eccentric grooves *d* which are cut in each of the side faces of the wheel *a*.

35 The wheel *a* is preferably formed by cutting a disk from a piece of wood, and the grooves *d* are cut in each of the side faces of the wheel *a* by rotating the wheel eccentrically. The handle *b* is bifurcated or forked at its forward end so as to straddle the wheel, as is most clearly shown in Figs. 2 and 3. The wheel is provided with a centrally disposed aperture into which snugly fits a bushing 10, and the wheel and bushing are journalled on a metal sleeve 13 clamped between the arms 11 of the handle by a rivet 12. The bushing 10 is adapted to fit closely but rotate freely on the sleeve 13 which extends beyond the side faces of the wheel *a*, thus holding the arms 11 of the forked handle apart so that they cannot be clamped

against the rotary unit comprising the wheel and bushing and thereby bind the same against free rotary movement. By peening the rivet 12 sufficiently, the sleeve 13 is held against rotation between the arms 11 of the handle. Thus, it will be seen that the wheel is secured to the handle in a very simple, easy and cheap manner while, at the same time, this connection is very effective in that it provides for the wheel a relatively large bearing on the bushing, and binding of the wheel is guarded against. The figure or horse preferably consists of two side members 14, each having the outline of a horse, and these side members being connected together by a central member or members 15 to which the side members are nailed or glued, as desired. The side members 14, as clearly shown in Fig. 3, straddle, at their forward ends, the wheel *a*, and the pegs *e* 75 of the side members are projected inwardly so as to freely engage the respective eccentric grooves *d*. The pegs *e* are secured to the side members by gluing or otherwise. The figure, at its rear end, is provided with 80 a depending lug 16 which is pivoted between the rear ends of the forked arms 11 of the handle, as by means of a pin 17.

With the construction described, it will be understood that the toy is operated by 85 pushing or rolling the wheel over a floor, thereby causing the eccentric grooves *d* to rotate and, as the figure rests upon the cams provided by these eccentric grooves, it will be raised and lowered assimilating a galloping or running movement. All of the parts of the device are very simple in construction and may be made of wood or other relatively cheap material so that the cost of manufacturing the parts is very low, and 90 these parts may be very readily assembled together in the manner described.

I claim as my invention:

1. A toy having a wheel in the form of a disk having an eccentric cut in each side, a bushing fixed in the center of said wheel, a handle having a bifurcated or forked end, the arms of which straddle said disk and bushing, a sleeve of greater axial length than said bushing clamped between the arms 100 of said handle and upon which said wheel and bushing are journalled, a figure of an animal straddling said disk and resting upon said eccentricities, said figure having a part extending down between the arms of said handle 105 110

2
dle rearwardly of said disk, and a pin for pivotally connecting the part to said arms of said handle.

2. A toy having a wheel consisting of a
5 wooden disk, an eccentric groove cut in each
of the side faces of said wheel, a bushing in
the center of said disk, a wooden handle
bifurcated at its forward end to provide
10 arms straddling said wheel and bushing, a
sleeve on which said wheel and bushing are
journalled and positioned between the arms
of said handle, a rivet or the like passing
through the arms of said handle and said
15 sleeve adapted to clamp said arms against
the ends of said sleeve to hold the latter
against rotary and endwise movement, a
figure of an animal comprising two side
members and a central part to which said
20 side members are connected, said side mem-
bers, at their forward ends, straddling said
wheel and having pegs engaging in said ec-
centric grooves, said figure having a depend-
ing part extending between the arms of said
handle rearwardly of said wheel, and a pin

extending through said arms and part for
pivotally connecting said figure for rocking
motion under the influence of said eccentric
grooves when said wheel is rolled on a sur-
face.

3. A toy comprising a handle bifurcated 30
at its forward end, a disk centrally jour-
naled between the furcations of said handle
and having coinciding eccentric grooves cut
in its side faces, a figure comprising similar
35 side elements, means for immovably connect-
ing said elements and holding them spaced
a greater distance than the axial thickness
of said disk, a lug depending from between
the rear portions of said spaced elements
40 and fastened thereto, said lug being jour-
naled at its lower end between the furca-
tions of said handle rearwardly of the per-
iphery of said disk, and concentric pins
projecting inwardly from the lower front
45 ends of said spaced elements and received
in said grooves.

FENELON McCOLLUM, JR.
